REVOLVING DOOR SPEED CONTROL

Thurloe M. Hagenbook, Evansville, Ind., assignor,
by mesne assignments, to International Door
Company, Evansville, Ind., a corporation of
Illinois

Application December 17, 1934, Serial No. 757,952

17 Claims. (Cl. 188—180)

My invention relates broadly to speed control mechanism and more particularly to a construction of speed control mechanism for revolving doors.

5 My invention is directed to that class of speed control mechanism for revolving doors of the type shown in my Patent 1,946,160, granted February 6, 1934, based on application filed September 10, 1932; and my copending application 689,633, filed 10 September 15, 1933, for Revolving door speed control now Patent 2,029,318, granted February 4, 1936.

15 One of the objects of my invention is to provide a highly compact construction of speed control for revolving doors, whereby the speed control may be installed and operated in confined places.

20 Another object of my invention is to provide a construction of speed control for revolving doors, in which the speed at which the mechanism becomes operative for the control of the revolving doors may be readily adjusted from a position adjacent the revolving door.

25 Still another object of my invention is to provide a construction of speed control mechanism for revolving doors which is also effective to brake the rotation of the door under conditions of sharp deceleration.

30 A further object of my invention is to provide a construction of revolving door speed control in which a centrifugally operated mechanism is effective to retard excessive acceleration, and in which an auxiliary mechanism is provided for effectively braking the door under conditions of rapid deceleration.

35 A still further object of my invention is to provide a simplified construction of centrifugally operated mechanism for revolving doors, and a co-acting cam actuated mechanism for controlling the speed of the revolving door, and braking the revolving door under conditions of rapid deceleration.

40 Other and further objects of my invention reside in the construction and arrangement of parts of the revolving door speed control set forth more 45 fully in the specification hereinafter following by reference to the accompanying drawings, in which:

45 Figure 1 is a top plan view of my improved speed control used in connection with the control of revolving doors; Fig. 2 is a central vertical longitudinal section through the speed control mechanism, taken substantially on line 2—2 of Fig. 1 and showing the elements in normal position; Fig. 3 is a transverse vertical section taken substantially on line 3—3 of Fig. 1, but showing the

centrifugal mechanism in position for braking the revolving door under conditions of excess speed; Fig. 4 is a similar view showing the position of the tumblers, friction wheel, and friction disc under conditions of excessive deceleration 5 which will result in the stoppage of the revolving of the door; Fig. 5 is a horizontal section taken on line 5—5 of Fig. 4 looking in the direction of the arrows; Fig. 6 is a horizontal section through the revolving door speed control mechanism taken 10 on line 6—6 of Fig. 2; Fig. 7 is a detailed horizontal section through the tumbler supporting housing taken substantially on line 7—7 of Fig. 8; Fig. 8 is a central vertical longitudinal section taken on line 8—8 of Fig. 7; Fig. 9 is a detailed top 15 plan view of the housing containing the mechanism for the improved speed control; Fig. 10 is a central vertical longitudinal section taken on line 10—10 of Fig. 9; Fig. 11 is a transverse vertical section on an enlarged scale taken on line 11—11 20 of Fig. 9; Fig. 12 is a top plan view of the cover plate used in association with the housing; Fig. 13 is a central vertical longitudinal section of the same, taken on line 13—13 of Fig. 12; Fig. 14 is a detailed central vertical longitudinal section of 25 one of the brake elements used in connection with my improved speed control; Fig. 15 is a top plan view thereof; Fig. 16 is a detailed side elevation of one of the centrifugally operated tumblers; Fig. 17 is a front elevation thereof; Fig. 18 is a 30 horizontal section taken on line 18—18 of Fig. 16; Fig. 19 is a horizontal sectional view taken on line 19—19 of Fig. 2; and Fig. 20 is a detail view of a portion of Fig. 19 showing parts in an operating position.

35 Referring to the drawings in detail, the speed control mechanism is shown mounted within the casing located adjacent the top of the revolving door structure. The casing is formed by a multiplicity of coacting parts which I have represented by characters 1, 2, 3, and 4. The several parts of the housing are shaped to provide bearing supports, and arranged to conform with the contour of the elements constituting the parts of the speed control mechanism. It will be noted 40 that part 1 is recessed at 1a and is apertured at 1b to allow the passage of shaft 5, and to provide a housing for the roller bearing structure 20. The part 4 of the casing is recessed at 4a and is apertured at 4b to allow the passage of the lower 50 end of shaft 5 and to form a housing and support for the roller bearing structure 21. The shaft 5 has a diametrically extending aperture 5a therein, through which the laterally extending member 24 projects. The laterally extending member 24 55

is connected with block 19 centered concentrically with respect to the internal tubular portion of shaft 5. The block 19 is balanced between two coil springs 28, and 28' as will be more fully described hereinafter. The upper coil spring 28 fits within the socket portion 5b of shaft 5. The lower coil spring 28' fits between the block 19 and the adjustable plug 29, which is screw-threaded into the lower end of the tubular shaft 5. The adjustable plug 29 has a tool receiving socket 29a, into which a suitable wrench may be inserted for varying the effective tension on the lower coil spring 28 as the screw-threaded plug 29 is advanced or retracted with respect to the internally screw-threaded shaft 5. The casing of the speed control mechanism is so mounted with respect to the revolving door structure, that the adjustable plug 29 may be readily engaged by a tool inserted through the aperture 35 in the ceiling structure 36, adjacent the revolving door assembly represented generally at 37 and 38.

The entire casing structure of the revolving door speed control is such that the casing will readily fit between the beams 38, on which the channel irons or rails 39 are erected. A portion of the casing 3 depends downwardly between the rails 39, thereby allowing installation of the speed control equipment in a confined space.

The revolving door assembly comprising revolving door wings 37 is carried by shaft 40, the upper end of which is supported by the wheeled carrier 41 having rollers 42 which are guided by the rails 39. The spindle 43 which is driven by the revolving door positively drives shaft 18 which is keyed by suitable key and keyway to the gear 11. The gear 11 is formed by an annular portion having a depending skirt with the edge thereof milled to provide gear teeth represented at 11a which mesh with the gear 12 which is journaled by on stud 15 serving as an axis for the ball bearing mounting 23 for the gear 12. The gear 12 is, in turn, meshed with the teeth of gear 13 mounted on shaft 13a. Shaft 13a is journaled in suitable bearings represented at 22. The bearings 22 are mounted in recesses provided in parts of the casing 1 and 2. The casing shown at 1 has a lower recess therein shown at 1c. The casing section 2 has an upwardly projecting recess therein shown at 2a, which recesses serve as enclosures for the bearings 22 which support the shaft 13a. The shaft 13a carries the gear 14 which meshes with the gear teeth 5c which are cut in the upper end of the shaft 5. The shaft 5 provides a mounting for the friction disc 10 which is secured to shaft 5 by means of a key and keyway represented at 10a which allows friction disc 10 to be positively driven by shaft 5 and yet, which permits the displacement of friction disc 10 in position along the axis of the shaft. The friction disc 10 has a hub portion formed integrally therewith terminating in the lower edge portion which is provided with a multiplicity of serrations forming a plurality of step-by-step cam surfaces indicated at 10c. The cam surfaces 10c coact with correspondingly shaped successive cam surfaces 8c formed on the hub portion 8b of the circular carrier 8. The circular carrier 8 is provided with aligned apertures 8a in the rotatable sleeve portion thereof through which the laterally extending member 24 passes. The apertures 8a are vertically extending slots, larger in cross-section than the bar 24 which permits the bar to move vertically in the aligned slots. The circular carrier 8 is provided with a plurality of oppositely

disposed pockets 8d which provide housings for centrifugal weights 9. The construction of centrifugal weights 9 is shown more clearly in Figs. 16, 17 and 18. It will be seen that the weights are not positively connected with the circular carrier 8, but are so shaped by means of the projecting portion 9a thereon that under conditions of centrifugal force produced by rotation of circular carrier 8, the center of gravity of weights 9 which is above the point of contact of the projecting portions 9a tends to travel outwardly. The displacement of the center of gravity of the weights 9 results in a rocking movement of weights 9 from the position illustrated in Figs. 2 and 4 to the position illustrated in Fig. 3. The outward rocking of 15 the weights 9 results in an upward displacement of the weights in the position illustrated in Fig. 3 placing an upward thrust on the lower face of the friction wheel 6. The friction wheel 6 has a frusto-conical friction surface 6a which tends to 20 frictionally engage a correspondingly shaped frusto-conical surface 3a formed on the interior wall of section 3 of the housing. A predetermined speed of rotation must be reached in order to bring about that degree of centrifugal force necessary 25 to rock the weights 9 for exerting the upward shift on friction disc 6.

The friction disc 6 is counterbalanced by means of coil springs 28 and 28' coacting with block 19. Block 19 carries laterally extending member 24, which, in turn, carries friction wheel 6. The laterally extending member 24 is smaller in cross-section than the aligned apertures 5a which extend circumferentially partly around shaft 5, as shown more clearly in Fig. 19, so that the carrier 8 is free to shift or rotate with respect to shaft 5 within limits which are sufficient to allow shifting of the cam shaped faces 8c with respect to the cam shaped faces 10c of friction disc 10. The upper coil spring 28 tends to resist the upward movement of friction wheel 6 while the lower coil spring 28' tends to assist the upward movement of friction wheel 6. The path of movement of friction wheel 6 is guided by key and keyway connection 6b. By provision of the adjustment plug 29, the degree of centrifugal force, necessary to bring about the upward thrust of friction wheel 6 and overcome the unbalanced condition of coil springs 28 and 28', may be determined with a high degree of precision. To 50 vary the control of speed, it is only necessary to vary the tension on the lower coil spring 28' by adjustment of plug 29.

When the door is sharply decelerated, the friction wheel 6 and the carrier 8 and centrifugal weights 9 and associated parts become an independent driver and operate to expend their kinetic energy. In other words, the mass of the carrier 8 and centrifugal weights 9 is such that the carrier 8 and centrifugal weights 9 tend to continue their rotative movement while friction disc 10 decelerates with the deceleration of shaft 5. This independent driving power tends to move the serrations constituting the plurality of cam faces 8c faster than the rotation of serrations or 65 cam faces 10c on friction disc 10, as a result of which, friction disc 10 is raised or forced upwardly, guided by key and keyway 10a, thereby driving friction disc 10 into frictional engagement with the friction surface 31 on part 1 of 70 the casing. The frictional contact thus established tends to bring shaft 5 to a stop thereby bringing the revolving doors to a standstill. Thus, it will be seen that rapid deceleration tends to brake the revolving door.

The several stages of operation of the revolving door speed control will be understood more clearly by considering the normal position of the parts illustrated in Fig. 2, and the successive 5 positions of the parts illustrated in Figs. 3 and 4. In Fig. 2, the rotatable carrier 8 and the centrifugal weights 9 are shown in normal position, such as is experienced when rotating the revolving doors at normal speed. In this position, 10 the frusto-conical face 6a of friction wheel 6 is disengaged from the frusto-conical face 3a of casing 3, and friction disc 10 is driven in disengaged relation with respect to friction surface 31. This condition continues so long as the 15 relative speed of the revolving doors does not exceed a predetermined value, or is not abnormally decelerated. The normal relative position of the shaft 5 and carrier 8 is shown in Fig. 19, wherein shaft 5 drives carrier 8 through the connection 20 by bar 24.

When the centrifugal action of weights 9 is brought into effect by an excessive speed of rotation, the friction wheel 6 is lifted, as illustrated in Fig. 3 for frictionally engaging the frusto-conical face 6a thereof with the coacting frusto-conical face 3a of casing 3. The relative position of shaft 5 and carrier 8 as shown in Fig. 19 is not changed in this operation, bar 24 having been displaced vertically in slots 5a and 8a upon 30 the raising of friction wheel 6; and thus friction disc 10 is not displaced in position under these circumstances and continues to idly revolve in disengagement with respect to friction surface 31. Braking of the revolving door is, therefore, effected for accelerated speeds.

Upon condition of sharp deceleration, however, the centrifugal weights 9 resume their normal position in pockets 8d of carrier 8, and the friction wheel 6 drops downwardly disengaging with respect to friction surface 3a of casing section 3. The mass of the friction wheel 6, the carrier 8, and the weights 9 is such, however, that their speed of rotation does not decelerate at the same rate as the speed of the friction disc 10 and hence, 45 these parts operate as a driver, as heretofore explained. Referring to Fig. 19, when hub 8b becomes the driving shaft, bar 24 is controlled thereby and carried ahead of shaft 5 in the slots 5a, as shown in Fig. 20. The cam faces 8c formed on the hub 8b force cam faces 10c upwardly, thereby engaging friction disc 10 with friction surface 31 resulting in the braking of 50 shaft 5 to which friction disc 10 is keyed through key and keyway 10a as represented in Fig. 4.

The driving ratio between the revolving door and the shaft 5 is approximately 1:25. That is to say, for each turn of shaft 18, there are twenty-five turns imparted to shaft 5. When the shaft 5 is rotated at too high a speed, the centrifugal mechanism becomes effective to brake shaft 5. However, if the deceleration of the revolving door becomes too great, the auxiliary braking mechanism constituted by friction disc 10 and friction surface 31 becomes effective to brake 65 shaft 5.

It will be understood that the braking mechanism is constituted by two independent systems which are not operative simultaneously, but successively. That is, at the time friction wheel 6 has the friction surface 6a thereof in engagement with friction surface 3a, the friction wheel 10 is free of engagement with friction surface 31. Conversely, at the time that friction wheel 6 has its friction surface 6a out of engagement 70 with friction surface 3a, the friction wheel 10

may be engaged with friction surface 31, if conditions of excessive deceleration should exist.

It will be understood that there is sufficient lost motion permitted in the movement of friction wheel 6 to permit the displacement of friction wheel 6 according to the displacement and position of the weights 9. The friction wheel 6 is secured in position by means of bolts 30 which extend through the friction wheel and into plate 7. Plate 7 serves to confine laterally extending 10 member 24 in position, which member has its opposite ends fitting somewhat loosely in sockets 6c disposed in friction wheel 6. The oppositely disposed slots 5a in shaft 5 and 8a in carrier 8 are of such size that friction wheel 6 is free to be 15 displaced vertically under control of the centrifugal weights 9. Likewise carrier 8 and block 19 are mounted with respect to shaft 5 so as to rotate freely with respect thereto by the force of momentum under conditions of excessive deceleration of shaft 5.

The housing for the several parts of the speed control has been heretofore described in general terms and reference is made to Figs. 9-15 for a more detailed disclosure of the several parts constituting the housing. It will be seen that section 1 of the casing is so shaped as to provide a compact housing for the inverted gear 11 by the coaction of the upwardly projecting annular portion 1d with the peripheral portion 1e. Section 1 of the casing is supported, as shown more clearly in Figs. 9 and 11 by means of flanges 1f having web members 1g interconnecting the flanges 1f with the casing 1. The support for the shaft 15 is indicated at 1h adjacent the housing 1c which receives the ball race 22. The closure for the casing indicated at 2 is secured in position with respect to the flanged edge of section 1 of the casing by means of a coacting flange 2b and a plurality of bolt members 26.

I provide a special journal for mounting shaft 18 which I have indicated by means of sleeves 16 and 17 concentrically disposed interiorly of the upwardly extending annular portion of section 1 indicated at 1d.

The friction wheel 6 is shown more particularly in Figs. 14 and 15 from which the interior construction of the friction wheel will be clear. The recesses disposed internally in the friction wheel 6 serve as seats for the plate 7 and the laterally extending member 24 secured in position by means of the bolts 30 extending through apertures 6d provided in the friction wheel.

The revolving door speed control of my invention comprises a relatively small number of parts and is relatively simple and inexpensive in production. I have found the arrangement of the parts of the mechanism highly practical and, while I have described my invention in one of its preferred embodiments, I desire that it be understood that modifications may be made and that no limitations upon my invention are intended other than are imposed by the scope of the appended claims.

What I claim as new and desire to secure by Letters Patent of the United States is as follows:

1. Speed control mechanism comprising a frame structure, a shaft member rotatably mounted with respect to said frame structure and connectible with driving means, a train of gears driven by said shaft member, a driven shaft operated by said train of gears, centrifugal mechanism operated by said driven shaft, a brake

- controlled by said centrifugal mechanism under conditions of excessive speed of the driving means, and an auxiliary brake operative under conditions of excessive deceleration of said driving means.
2. Speed control mechanism comprising a frame structure, a shaft member journaled with respect to said frame structure and connectible with driving means, a driven shaft journaled with respect to said frame structure, a gear train interconnecting said driven shaft with said shaft member, and a pair of braking devices disposed concentrically with respect to said driven shaft, one of said braking devices being operative to brake said driving means under conditions of excessive speed and the other of said braking devices operating to bring the driving means to a stop under conditions of excessive deceleration.
3. Speed control mechanism comprising a frame structure, a shaft member journaled with respect to said frame structure and connectible with driving means, a driven shaft journaled with respect to said frame structure, a gear train interconnecting said driven shaft with said shaft member, a centrifugal device operated by said driven shaft, a braking member operative under control of said centrifugal device under conditions of excessive speed of the revolving door, and a separate braking member concentrically disposed with respect to said driven shaft and operating to brake the revolving door under conditions of excessive deceleration.
4. Speed control mechanism comprising a frame structure, a shaft member journaled with respect to said frame structure and connectible with driving means, a driven shaft journaled with respect to said frame structure, a gear train interconnecting said driven shaft with said shaft member, a centrifugal device operated by said driven shaft, a braking mechanism operated by said centrifugal device for braking the revolving door under conditions of excessive speed, and a separate device operative by force of momentum for braking the driving means under conditions of excessive deceleration.
5. Speed control mechanism for revolving doors comprising a driven shaft, means for imparting rotation to said driven shaft in proportion to the rotary movement of the revolving door, centrifugal mechanism operated by said driven shaft, a braking device controlled by said centrifugal mechanism for bringing the revolving door to a safe speed and operative under conditions of excessive rotary speed, and separate means for bringing the revolving door to a stop and operative under conditions of excessive deceleration.
6. Speed control mechanism for revolving doors comprising a driven shaft, means for imparting rotation to said driven shaft in proportion to the rotary movement of the revolving door, centrifugal mechanism operated by said driven shaft, a braking device controlled by said centrifugal mechanism for bringing the revolving door to a safe speed and operative under conditions of excessive rotary speed, separate means for bringing the revolving door to a stop and operative under conditions of excessive deceleration, and means for predetermining the speed of rotation of said driven shaft at which said centrifugal mechanism becomes effective for braking the revolving door.
7. Speed control mechanism for revolving doors comprising a driven shaft, means for imparting rotation to said driven shaft in proportion to the

rotary movement of the revolving door, centrifugal mechanism operated by said driven shaft, a braking device controlled by said centrifugal mechanism for bringing the revolving door to a safe speed and operative under conditions of excessive rotary speed, separate means for bringing the revolving door to a stop and operative under conditions of excessive deceleration, and an adjustable spring device operative for predetermining the speed of rotation of said driven shaft at which said centrifugal mechanism becomes effective for braking the revolving door.

8. Speed control mechanism comprising a rotary driving shaft, a driven shaft, a train of gears interconnecting said driven shaft with said rotary driving shaft, a friction wheel carried by said driven shaft, centrifugal mechanism operative with respect to said friction wheel under conditions of excessive speed for braking said rotary shaft, and an auxiliary braking device concentrically mounted with respect to said driven shaft and operative with said friction wheel in disengaged position for effectively stopping said rotary shaft under conditions of excessive deceleration.

9. Speed control mechanism for revolving doors comprising a casing, a master gear journaled in said casing, a driving shaft interconnecting said master gear with the rotary actuator of a revolving door, a gear train mounted in said casing and driven by said master gear, a driven shaft mounted in said casing and operated by said gear train, centrifugal mechanism and momentum mechanism carried by said driven shaft, and a pair of braking devices disposed concentrically with respect to said driven shaft, one of said braking devices being operative under control of said centrifugal mechanism for retarding the rotation of the revolving door under conditions of excessive speed, and the other of said braking devices operative under control of said momentum mechanism to stop the rotation of the revolving door under conditions of excessive deceleration.

10. Speed control mechanism comprising a housing, a driving shaft and a driven shaft journaled with respect to said housing, a train of gears interconnecting said shafts, centrifugal mechanism mounted with respect to said driven shaft, a friction wheel floatingly supported with respect to said driven shaft and operative under the control of said centrifugal mechanism for retarding the movement of the driving shaft under conditions of excessive speed, an auxiliary friction device mounted concentrically with respect to said driven shaft, and cam mechanism for shifting said auxiliary friction device into frictional engagement under conditions of excessive deceleration for bringing the said driving shaft to a stop.

11. Speed control mechanism comprising a driving shaft, a driven shaft, a housing for mounting said driving and driven shafts, a gear train interconnecting said shafts, said driven shaft having an axial recess therein for receiving a pair of coil springs, a block member disposed between said coil springs, a laterally extending rod member projecting through said block member and through diametrically opposite apertures in said driven shaft, a friction wheel suspended on said laterally extending rod member, a centrifugal device operated by said driven shaft for shifting said friction wheel into frictional engagement with a portion of said housing under conditions of excessive speed for retarding the rotation of said driving shaft.

12. Speed control mechanism comprising a

- driving shaft, a driven shaft, a housing for mounting said driving and driven shafts, a gear train interconnecting said shafts, said driven shaft having an axial recess therein for receiving a pair of coil springs, a block member disposed between said coil springs, a laterally extending rod member projecting through said block member and through diametrically opposite apertures in said driven shaft, a friction wheel suspended on said laterally extending rod member, a centrifugal device operated by said driven shaft for shifting said friction wheel into frictional engagement with a portion of said housing under conditions of excessive speed for retarding the rotation of said driving shaft, and means for adjusting said coil springs for predetermining the speed at which said centrifugal mechanism becomes effective to move said friction wheel into engagement with the coacting portion of said housing.
13. Speed control mechanism comprising a driving shaft, a driven shaft, a housing for mounting said driving and driven shafts, a system of gears interconnecting said shafts, a carrier concentrically disposed about said driven shaft, centrifugally operated weights mounted in said carrier, a friction wheel concentrically disposed about said driven shaft and above said carrier, said friction wheel being shiftable into friction engaging position with respect to said housing under conditions of displacement of said centrifugally operated weights for retarding the movement of said shaft upon excessive speed of the driving shaft, spring means for predetermining the speed at which said centrifugally operated weights become effective to displace said friction wheel, and an auxiliary friction device disposed concentrically with respect to said driven shaft and effective under excessive deceleration of the driving shaft for bringing said shaft to a stop.
14. Speed control mechanism comprising a driving shaft, a driven shaft, a housing for mounting said shafts, means in said housing for transmitting rotary motion from said driving shaft to said driven shaft, a carrier disposed concentrically of said driven shaft, centrifugally operated weights mounted in said carrier, a friction wheel extending laterally with respect to said carrier and shiftable with respect to said driven shaft in accordance with the variable displacement of said centrifugally operated weights, spring means for counterbalancing the mass of said friction wheel with respect to the mass of said centrifugally operated weights, means for adjusting the tension on said spring means from the exterior of said housing whereby said friction wheel is adapted to be moved into frictional engagement with a portion of said housing at a predetermined rotative speed of said driven shaft,

and a friction disc concentrically mounted with respect to said driven shaft and effective under conditions of excessive deceleration for bringing the driving shaft to a stop.

15. In a speed control mechanism, a casing, a driving shaft and a driven shaft journaled along vertical axes with respect to said casing, means in said casing for transmitting motion from said driving shaft to said driven shaft, a laterally extending carrier concentrically mounted with respect to said driven shaft, a friction wheel extending directly over said carrier, spring means disposed within an axial recess in said driven shaft, a laterally projecting member extending through aligned apertures in said driven shaft and in said carrier for resiliently suspending said friction wheel with respect to said carrier and the spring means housed within said driven shaft, centrifugally displaceable weights in said carrier operative for shifting said friction wheel into engagement with a portion of said housing for retarding the driving shaft under conditions of excessive speed, and an auxiliary friction disc disposed concentrically of said driven shaft and operative under conditions of excessive deceleration for bringing the driving shaft to a stop.

16. In a speed control mechanism, a casing, a driving shaft and a driven shaft journaled along vertical axes with respect to said casing, means in said casing for transmitting motion from said driving shaft to said driven shaft, a laterally extending carrier concentrically mounted with respect to said driven shaft, a friction wheel extending directly over said carrier, spring means disposed within an axial recess in said driven shaft, a laterally projecting member extending through aligned apertures in said driven shaft and in said carrier for resiliently suspending said friction wheel with respect to said carrier and the spring means housed within said driven shaft, centrifugally displaceable weights in said carrier operative for shifting said friction wheel into engagement with a portion of said housing for retarding the driving shaft under conditions of excessive speed, a plurality of cam faces on a portion of said carrier, an auxiliary friction disc having coacting cam faces, said cam faces being operative under conditions of excessive deceleration for forcing said auxiliary friction disc into frictional engagement with a different portion of said casing.

17. Speed control mechanism comprising centrifugally operated braking means for controlling the maximum running speed of a shaft; and separate, momentum operated, braking means for abruptly stopping the shaft under conditions of excessive deceleration; said braking means cooperating to effect safe operation of the shaft.

THURLOE M. HAGENBOOK.
